(57) **CLAIM**

The ornamental design for an imaging device, as shown and described.

DESCRIPTION

FIG. 1 is a top, front, left perspective view of an imaging device in accordance with our new design;

FIG. 2 is a front elevational view of the imaging device shown in FIG. 1;

FIG. 3 is a rear elevational view of the imaging device shown in FIG. 1;

FIG. 4 is a left-side elevational view of the imaging device shown in FIG. 1;

FIG. 5 is a right-side elevational view of the imaging device shown in FIG. 1;

FIG. 6 is a top plan view of the imaging device in FIG. 1; and,

FIG. 7 is a bottom plan view of the imaging device shown in FIG. 1.

The broken lines shown in the drawings represent portions of the imaging device that form no part of the claimed design.

1 Claim, 7 Drawing Sheets
